UNITED STATES PATENT OFFICE

JO D. BERWICK, OF AKRON, OHIO, ASSIGNOR TO THE GOODYEAR TIRE & RUBBER COMPANY, OF AKRON, OHIO, A CORPORATION OF OHIO

DESIGN FOR RUBBER OR SIMILAR MATERIAL

Application filed September 24, 1929. Serial No. 32,855. Term of patent 14 years.

To all whom it may concern:

Be it known that I, Jo D. BERWICK, a citizen of the United States, residing at Akron, in the county of Summit and State of Ohio, have invented a new, original, and ornamental Design for Rubber or Similar Material, of which the following is a specification, reference being had to the accompanying drawing, forming part thereof.

Fig. 1 is a plan view of a piece of rubber or similar material showing my new design; and

Fig. 2 is a cross-sectional view taken substantially along the line II—II of Figure 1.

I claim:

The ornamental design for rubber or similar material, as shown.

JO D. BERWICK.
